DEVICE, MORE PARTICULARLY MANIFOLD WRITING DEVICE FOR ISSUING TICKETS OR THE LIKE

Horace Drummond Black, London, and Christopher Frederick Webb, Eastcote, England, assignors to Bell Punch Company Limited, London, England

Application September 10, 1934, Serial No. 743,470
In Great Britain March 5, 1934

18 Claims. (Cl. 282—16)

This invention is for improvements in or relating to devices more particularly to manifold writing devices for issuing tickets, bills, receipts and the like (hereinafter referred to as tickets) upon which certain data is inscribed by the operator prior to issue, and in which it is usual for one or more copies to be recorded upon one or more superimposed duplicate forms, and in which, if necessary, one duplicated form is retained in the device for the purpose of identifying and checking transactions made by means of the device. In such devices the tickets are arranged in the form of a fan-fold strip or roll in a magazine contained in the machine, and are fed forwardly and delivered externally to the device one at a time with each operation of the device usually by pin feed mechanism.

The device which constitutes the subject matter of this invention is of the type wherein the tickets or the like are arranged in the form of a single strip or two or more superimposed strips in a magazine and are fed by means of a pin wheel or the like engaging with perforations in the strip so as to feed at least one ticket from the strip, or from each of the two or more superimposed strips upon each actuation of the device.

According to the present invention there is provided a device of the type referred to, wherein means arranged to feed the ticket strip through the device is actuated by a yieldingly controlled mechanism which is automatically released by a trigger action to feed a ticket from the device.

Again, according to the invention there is provided a device of the type referred to, wherein means arranged to feed the ticket strip forwardly through the device is operable by a mechanism which is arranged to be moved in one direction against the tension of a spring by a manually operable trigger device and is arranged to be released automatically therefrom, after the said trigger device has been displaced a predetermined distance, to move under the action of the spring in the reverse direction and thereby cause the ticket strip to be fed forwardly through the device.

The invention will be more particularly described with reference to the accompanying drawings in which:—

Figure 1 illustrates a front elevation of the device with the cover of a casing in section;

Figure 2 illustrates a side elevation of the device with the side of the cover of the casing cut away;

Figure 3 illustrates a front elevation of the

device with the cover of the casing and a cover plate for the actuating mechanism removed;

Figure 4 is a plan view of the device;

Figure 5 illustrates a portion of the actuating mechanism shown in Figure 3 but in a different 5 position;

Figure 6 is a section on the line 6—6 of Figure 2 and illustrates a detail of the mechanism shown in Figure 1;

Figure 7 illustrates diagrammatically a modification of a portion of the actuating mechanism, and

Figure 8 illustrates diagrammatically a further modification of a portion of the actuating mechanism.

Referring to Figures 1 to 6 of the drawings, a cover 1 of a casing of a manifold writing device is illustrated as hinged to a base plate 2 by means of a hinge 3. The cover 1 is provided on the exterior thereof with a ticket punching device 4 known per se and an actuating hand lever 5 which is connected by means of a spindle 6 to actuating mechanism disposed on the base plate 2. A cover plate 7 is arranged to protect the actuating mechanism shown in Figure 3 and is provided with a vertical partition 8 which divides the space between the plate 7 and the inner side of the cover 1 into two compartments.

A series of tickets arranged in a strip are disposed in a fan folded manner within the right hand compartment (Figure 1) together with a duplicated strip therefor. The superimposed strips are fed over a roller 9, around a drum 11 between the latter and a guide 10, and thereafter over a platen 13 preferably provided with a milled 35 surface. The superimposed strips are fed over the platen in such a manner that a strip of carbon paper or inked fabric 14 is disposed between the ticket and the duplicate strip. Consequently any inscription made upon the ticket to be issued 40 which is accessible for this purpose through an opening 15 in the casing, is duplicated upon the strip of duplicating paper which is thereafter fed by a drum 12 and guide 16 into the left hand compartment (Figure 1) and folded in a fan-like 45 manner, whilst the tickets are issued from the device through a slot 16 in a side wall of the casing 1.

The drum 11 which is arranged to engage respectively through the medium of pins 17 with 50 the ticket strip and the duplicating strip so as to feed the ticket and the duplicating strip over the platen 13, and the drum 12 which is arranged to receive only the duplicating strip and feed the same into the left hand compartment also by the 55

means of pins 18 disposed upon the said drum, are driven respectively from a Maltese wheel 19, the periphery of which is toothed to mesh with a pinion wheel 20 and with two pinion wheels 21 and 22 which are secured on the shafts of the pin drums 11 and 12 above referred to. The Maltese wheel 19 is arranged to be engaged by a pin wheel 23 operated in a manner hereinafter described so as to rotate the Maltese wheel 19 through an angle of 60° upon each actuation of the pin wheel the rotation of the Maltese wheel 19 effecting through the intermediary of the pinions 21 and 22 a half revolution to each of the drums 11 and 12. The pairs of pins 17 and 18 are diametrically opposed on the drums 11 and 12 and consequently the half revolution of each of the latter feeds the length of one ticket through the device.

The pin wheel 23 is operated by a trigger mechanism which comprises a hook shaped lever 24 arranged to pivot about a pin 32 disposed in an extension of a lever 26. The hook shaped lever 24 is capable of movement in a direction parallel to the lever 26 due to the provision of a slot therein which accommodates the pin 32. The lever 26 is pivoted at 25 and carries at the outer end thereof a roller 27 arranged to engage with the leading end of the hook shaped lever 24 so that the movement of the lever 26 in an anti-clockwise direction moves the hook shaped lever 24 also in an anti-clockwise direction until a nose 28 formed on the leading end of the said hook shaped lever 24 engages with a pin 29 and is thereby moved in a radial direction so as to be disengaged from the roller 27 carried on the said lever 26. The hook shaped lever 24 is then returned to the normal position thereof by a spring 30 operatively connected thereto. The lever 26 is arranged to be rotated by means of the hand lever 5 (Figures 1, 2, or 4) located on the outside of the casing 1 and connected to the lever 26 by means of the spindle 6. The hook shaped lever 24 is provided at the free end thereof with a surface 24a which as the lever 26 is moved from the initial to the loaded position rides over the surface of a pin 23a carried on the pin wheel 23, thereby maintaining the pin wheel in a definite position, but when the nose 28 of the leading end of the lever 24 engages with the fixed pin 29, the surface 24a of the lever 24 has moved clear of the pin 23a on the pin wheel 23 and consequently the movement of the hooked lever 24 in a radial direction takes place without engagement with the pin 23a of the pin wheel 23. The hooked lever 24 is displaced radially to the position shown in Figure 5 and when this lever is released by the nose 28 passing beyond the end of the roller 27 it engages with the pin 23a on the pin wheel 23 and thereby carries the pin wheel 23 with it and rotates the same through an angle of 120°. The rotation of the pin wheel 23 through an angle of 120° causes the Maltese wheel 19 to move through an angle of 60° and, as hereinbefore stated, the Maltese wheel 19 thereby effects a half revolution of each of the drums 11 and 12 arranged to feed the ticket and the duplicating strip over the platen 13 and also the duplicating strip into the left hand compartment.

The lever 26 which is operable to move the hook shaped lever 24 from the normal to the rotated position may be provided at the outer end thereof with a yielding head piece so as to enable the said lever 26 when returned under the influence of a spring 34 to the initial position upon the release of the handle 5, to snap under the nose 28 on the lever 24 so that it is thus set in

position in readiness for the device to be actuated again. In the arrangement shown however, when the lever 26 restores under the action of the spring 34, the nose 28 rides up against the tension of the spring 30 until the roller 27 is restored to the position shown in Figure 3 and then returns under the action of the spring 30 to the position shown in Figure 3. An arm 36 is provided on the hook shaped lever 24 and this engages the stop 38 on the return motion of the lever and thus limits the degree of movement of the latter.

The pinion 20 hereinbefore referred to which makes one complete revolution for every revolution of 60° by the Maltese wheel 19, oscillates an arm connected to a striker 37 which strikes the gong 38, the gong thus being sounded every time the Maltese wheel is rotated to issue a ticket.

A locking device operable from the exterior of the casing is provided for the purpose of rendering the machine inoperative when so desired. This locking device comprises a bar 39 pivoted on a further bar 40 which latter is pivoted on the base plate 2 of the machine by means of the pivot pin 41. The end of the bar 40 adjacent the pivot 41 is curved so as not to interfere with the pinion 20. The bar 39 is arranged to be moved in a direction towards the pin 29 by means of a projection 42 on a plate 43, which projection engages with a slot in the bar 39. The plate 43 is rotated by a pin, not shown, which projects through the back wall of the casing of the machine and moves in an arcuate slot. The plate 43 is spring urged to the position shown in Figure 3 but when this plate is rotated, a pin 44a carried on a plate spring 44 riveted to the plate 43 enters the hole 45 (Figure 1) in the cover plate 7 and prevents the restoration of the plate 43. The plate 43 is released by inserting a shaft pointed instrument in the hole 45 and releasing the pin 44a. The plate 43 and the bar 39 are then restored under spring control to the position shown in Figure 3. The bar 39 is provided at the free end thereof with a pin 46 which when the bar is in an operated position is located in the path of the nose 28. As the bar 39 is flush against the side wall of the cover 1, it consequently cannot rotate about its pivot and hence the pin 46 prevents the nose 28 moving to the extreme operative position when the lever 26 is rotated. The nose 28 of the lever 24 is not released from the roller 27 and the Maltese wheel 19 is not actuated.

In the modification of the present invention, illustrated in Figure 7, the Maltese wheel 19 is replaced by a star wheel 48 having three teeth each separated by an angle of 120°. The star wheel 48 is arranged to be engaged by a rod 49 which moves longitudinally and is provided at the free end thereof with two rollers 50 and 51. The roller 51 is arranged to engage with a guide block 52 which governs the path of movement of the rod 49 and the other roller 50 is arranged to engage with the free end of one of the teeth of the star wheel 48 in a manner hereinafter specified. At the end of the rod 49 remote from the star wheel 48 the same is connected by means of a pivotal link 53 with a second link 54 pivotally connected to a lever 55 arranged to be operated by the exterior hand lever 5 of the device. The rod 49 is provided at the pivoted end thereof with a depression 56 wherein the end of the pivotal link 53 is normally held by means of a spring 57, connected to the pivotal link 54 and the lever 55, which normally tends to press the end of the pivotal link 53 into the said depression. The rod 49 is maintained in the inoperative position by means

of a tension spring 58 and the pivoted end of the said rod 49 is shaped so as to roll over an eccentric 59 secured to the base plate 2 of the device for a purpose hereinafter specified.

5 The operation of the device is as follows:

When the lever 55 connected to the hand lever 5 of the device is moved in an anti-clockwise direction, the pivotal link 54 presses the pivotal link 53 against the depression 56 in the rod 49 and at 10 the same time moves the rod 49 in a longitudinal direction away from the teeth of the star wheel 48 in a downward direction. The rod 49 in so moving is guided in its course by a pin 60 on the base plate 2 and the guide block 52 until the pivotal axes of the two pivotal links 53 and 54 are in 15 line, whereupon the lower end of the rod 49 engages with the eccentric 59 so as to bring the pivotal connection between the two pivotal links below the line joining the other two pivotal axes 20 of the two pivotal links, thus releasing the rod 49 and permitting it to move upwardly under the tension of the spring 58 so that the roller 50 on the free end thereof engages with the next tooth of the star wheel 48 and moves it through 120°. 25 In order to prevent the star wheel from being moved as the rod 49 is being moved downwardly the star wheel 48 is provided with a pawl 61 which arrests the movement thereof after the rod 49 has ceased to operate and holds it in a position 30 which, when the rod 49 is released, ensures that the free end of the latter engages with the next succeeding tooth of the wheel 48.

A modification of the device just described, which is illustrated in Figure 8, consists in a hook shaped lever 62 being connected to a hand operated lever substantially similar in construction and operation to the lever 5 previously described, the hook 63 of the lever 62 being arranged to engage with a hook 64 formed on the end of the 40 rod 49' above referred to. The movement of the rod 49' is controlled by a trunnion block 67 arranged to slide in a groove formed in the base plate 2' of the device in such a manner that when the hooked lever 62 has been moved a predetermined distance, the trunnion block 67 on the rod 49' causes the two hooked projections 63 and 64 to move out of engagement with one another and release the rod 49' so that it engages with the next tooth of the star wheel of the device and rotates 45 the wheel through 120°. The free end of the rod 49' as hereinbefore stated is controlled by a guide block 65 and a pin 66, and the end of the rod 49' is provided with the roller 50' for engagement with the star wheel 48'. Further the hook shaped 50 lever 62 is provided with a pivoted free end 69 arranged to yield against the influence of a spring 10 when the hand lever is returned to the normal position thereby permitting the hooked shaped ends 63 and 64 of the lever 62 to engage once 55 more with one another.

It is to be understood that although the Maltese wheel and the star wheels hereinbefore referred to have been described as being connected through the medium of pinion wheels 21 and 22 60 with the feed drums 11 and 12 of the ticket mechanism, it is to be understood that the Maltese wheel 19 and the star wheels 48 may be directly connected to said drums.

In the devices hereinbefore described the duplicated strip is arranged to be fed in a fan-folded manner into the left hand receptacle. This is preferably accomplished by providing the second feeding drum 12 with an arcuate slot 11 (Figure 6) for one half of cylindrical surface 75 thereof, the other half of this surface being un-

slotted. Arranged to engage with the drum 12 is a device 72 in the shape of a bell crank lever, one arm 73 of which is arranged to engage with the drum, and the other arm of which is arranged to extend into the path over which the 5 duplicated strip is fed. The lever 72 is spring urged by means of a spring 74 so that during one half of a revolution of the drum 12 the arm 73 of the lever 72 extends into the interior of the drum 12 through the slot 11 thus allowing the 10 other arm to lie substantially tangentially to the surface of the drum 12 and thereby permitting the feed of the duplicated strip in one direction. For the remaining half revolution of the drum no 15 slot occurs and the arm 73 of the lever is displaced by the surface of the drum 12 against the influence of the spring 74 so as to bring the second arm of the lever 72 into a substantially radial position, where the duplicated strip is deflected 20 in a direction at right angles to the normal direction of the strip. It is found that with a simple arrangement of this character, the duplicated strip is fed in a fan-folded manner into the left hand compartment of the device.

Thus, it will be seen that with the trigger 25 mechanism hereinbefore referred to which is loaded through the medium of the handle 5 disposed on the exterior of the device, an operator can only actuate this exterior handle 5 so as to load the trigger mechanism for actuation but 30 the actual actuation and feeding of the ticket strip through the device is thereafter completely out of the operator's control as this is effected solely upon the release of the trigger mechanism 35 once it has been moved a predetermined distance, thus ensuring that the operator cannot manipulatively interfere with the ticket feed mechanism. Again due to the fact that the ticket feed is operated by a trigger mechanism, the operator can 40 tear off the ticket which has been issued from the device whilst the exterior handle 5 is being returned to the initial position and thus it will be seen that the device can be operated much more rapidly than if the feeding of the ticket through the device was dependent upon the operator alone and required the operator to move the handle both from the initial position to the 45 operative position and back again.

It is obvious that the device can be used as a simple ticket issuing machine without necessarily 50 employing the duplicate retaining facilities described.

What we claim and desire to secure by Letters Patent of the United States is:—

1. A strip ticket issuing machine comprising a 55 ticket strip supply magazine adapted to accommodate a supply of at least one ticket strip, a feeding device for the strip provided with means arranged to engage with perforations in the strip so as to feed said strip forwardly at least one 60 ticket length upon each actuation of the machine, a pivoted lever manual means for displacing said lever in one direction, a second lever operable under spring control to actuate said feeding device and pivotally connected at one end thereof to the said pivoted lever, a hook shaped lever disposed on the other end of said second lever which is arranged to engage with the free end of the 65 said pivoted lever so that the two levers are rotated together during the initial displacement in the said direction of the pivoted lever and means for releasing the said hook shaped projection from the free end of the pivoted lever during the 70 displacement of the latter so that the second lever 75

is free to rotate under spring control and actuate the feeding device.

2. A strip ticket issuing machine comprising a ticket strip supply magazine adapted to accommodate a supply of at least one ticket strip, a feeding device for the strip provided with means arranged to engage with perforations in the strip so as to feed said strip forwardly at least one ticket length upon each actuation of the machine, a pivoted lever manual means for displacing said lever in one direction, a second lever operable under spring control to actuate said feeding device and pivotally and slidably connected at one end thereof to the said pivoted lever, a hook shaped projection disposed on the other end of said second lever which is arranged to engage with the free end of the said pivoted lever so that the two levers are rotated together during the initial displacement in the said direction of the pivoted lever, a nose on said hook shaped projection, and a stationary pin, fixed relatively to the machine, which is arranged to engage with the said nose during the displacement of the pivoted lever and cause the said nose to ride up so that the hook shaped projection is released from the free end of the pivoted lever and the said section lever is free to rotate under spring control and actuate the feeding device.

3. A strip ticket issuing machine comprising a ticket strip supply magazine adapted to accommodate a supply of at least one ticket strip, a pin wheel, a radially slotted wheel operable by said pin wheel by the slots therein being engaged by the pins of the pin wheel, two feeding drums provided with projections arranged to engage with perforations in the strip and operable by said radially slotted wheel so as to feed said strip forwardly at least one ticket length upon each actuation of the machine, a normally ineffective spring, means operatively connecting the spring to the pin wheel for actuating the latter and trigger mechanism operable to load said spring and thereby render it effective to actuate said pin wheel and when fully loaded to release it.

4. A manifold writing device for issuing tickets comprising a ticket strip supply magazine adapted to accommodate a supply of at least two superimposed ticket strips, a feeding mechanism for the strip provided with means arranged to engage with perforations in the strips so as to feed each of said strips forwardly at least one ticket length upon each actuation of the device, means for feeding at least one strip to the interior of the machine and at least one strip to the exterior of the machine, a normally ineffective spring means operatively connecting the spring to the feeding mechanism to actuate the latter, and trigger mechanism operable to load said spring and thereby render it effective to actuate the feeding device when fully loaded to release it.

5. A manifold writing device for issuing tickets comprising a ticket strip supply magazine adapted to accommodate a supply of at least two superimposed ticket strips, a pin wheel, a radially slotted wheel operable by said pin wheel by the slots therein being engaged by the pins of the pin wheel, two feeding drums provided with projections arranged to engage with perforations in the strips and operable by said radially slotted wheel so as to feed each of said strips forwardly at least one ticket length upon each actuation of the machine, one of said drums having associated therewith means for feeding at least one strip to the interior of the machine and at least one

strip to the exterior of the machine, a normally ineffective spring means operatively connecting the spring to the pin wheel for actuating the latter and trigger mechanism operable to load said spring and thereby render it effective to actuate said pin wheel and when fully loaded to release it.

6. A strip ticket issuing machine comprising a ticket strip supply magazine adapted to accommodate a supply of at least one ticket strip, a feeding device provided with means arranged to engage with perforations in the strip so as to feed said strip forwardly at least one ticket length upon each actuation of the machine, a normally ineffective spring means operatively connecting the spring to the feeding device to actuate the latter, a pivoted lever arranged to be rotated under manual control, a rod connected to said spring and arranged to be displaced longitudinally by said pivoted lever for the purpose of tensioning the said spring, linkwork connecting said rod and pivoted lever, and means for rendering said linkwork effective during the rotation of the lever to allow automatically the restoration of the rod and enable the spring to become effective to drive said feeding device.

7. A strip ticket issuing machine comprising a ticket strip supply magazine adapted to accommodate a supply of at least one ticket strip, a feeding device provided with means arranged to engage with perforations in the strip so as to feed said strip forwardly at least one ticket length upon each actuation of the machine, a normally ineffective spring means operatively connecting the spring of the feeding device to actuate the latter, a pivoted lever arranged to be rotated under manual control, a hook shaped projection on the free end of said lever, a rod connected to said spring, a hook shaped projection on one end of said rod arranged to engage with the hook shaped projection on the free end of the lever so that the rod is displaceable longitudinally against the tension of the spring when the lever is rotated, and means for automatically disengaging said hook shaped projections during the rotation of the lever so that the rod restores and the spring becomes effective to drive said feeding device.

8. A strip ticket issuing machine comprising a ticket strip supply magazine adapted to accommodate a supply of at least one ticket strip, a feeding device provided with means arranged to engage with perforations in the strip so as to feed said strip forwardly at least one ticket length upon each actuation of the machine, a pivoted lever arranged to be rotated under manual control, a normally ineffective spring, a rod arranged to actuate said feeding device, connected to said spring and displaceable longitudinally by said pivoted lever against the tension of the spring, linkwork connecting said rod and pivoted lever, means for rendering said linkwork effective during the rotation of the lever to allow automatically the restoration of the rod, a guide block for guiding the rod during the longitudinal movement thereof, a star wheel operatively connected to said feeding device, and a roller disposed on the free end of said rod arranged to engage with said star wheel and effect rotation thereof upon the restoration of said rod, for the purpose of actuating said feeding device.

9. A strip ticket issuing machine comprising a ticket strip supply magazine adapted to accommodate a supply of at least one ticket strip, a feeding device provided with means arranged to

engage with perforations in the strip so as to feed said strip forwardly at least one ticket length upon each actuation of the machine, a pivoted lever arranged to be rotated under manual control, a hook shaped projection on the free end of said lever, a normally ineffective spring, a rod connected to said spring, a hook shaped projection on one end of said rod arranged to engage with the hook shaped projection on the free end 10 of the lever so that the rod is displaceable longitudinally against the tension of the spring when the lever is rotated, a guide block for guiding the rod during the longitudinal movement thereof and for automatically disengaging said hook shaped projections during the rotation of the lever so that the rod restores, a star wheel operatively connected to said feeding device and a roller disposed on the free end of said rod arranged to engage with said star wheel and effect 20 rotation thereof upon the restoration of said rod, for the purpose of actuating said feeding device.

10. A strip ticket issuing machine comprising a ticket strip supply magazine adapted to accommodate a supply of at least one ticket strip, 25 means normally inaccessible from the exterior of the machine for feeding forwardly from the supply of strip at least one ticket length thereof at each actuation of the machine, and yieldingly controlled trigger operated driving mechanism 30 for said feeding means operable from the exterior of the machine.

11. A strip ticket issuing machine comprising a ticket strip supply magazine adapted to accommodate a supply of at least one ticket strip, 35 means normally inaccessible from the exterior of the machine for feeding forwardly from the supply of strip at least one ticket length thereof at each actuation of the machine, a normally ineffective spring means operatively connecting 40 the spring to the feeding means to actuate the latter, and trigger mechanism operable from the exterior of the machine to load said spring and thereby render it effective to actuate the feeding means and when fully loaded to release 45 it.

12. A manifold writing device for issuing tickets comprising a ticket strip supply magazine adapted to accommodate a supply of at least two superimposed ticket strips, means normally inaccessible from the exterior of the device for feeding forwardly from the supply of strip at least one ticket length of each strip at each actuation of the device, a spring-loaded trigger operated driving mechanism for said 55 feeding means operable from the exterior of the device, and means for feeding the leading end of at least one of the superimposed strips to the exterior of the device and at least one to the interior of the device, upon each actuation of the 60 feeding means.

13. A strip ticket issuing machine comprising a ticket strip supply magazine adapted to accommodate a supply of at least one ticket strip, a feeding device for the strip normally inaccessible from the exterior of the machine and provided with means arranged to engage with perforations in the strip so as to feed said strip forwardly at least one ticket length upon each actuation of the machine, and yieldingly controlled trigger operated driving mechanism for 70 said feeding device operable from the exterior of the machine.

14. A strip ticket issuing machine comprising a ticket strip supply magazine adapted to accommodate a supply of at least one ticket strip, a

feeding device for the strip normally inaccessible from the exterior of the machine and provided with means arranged to engage with perforations in the strip so as to feed said strip forwardly at least one ticket length upon each actuation of the machine, a normally ineffective spring means operatively connecting the spring to the feeding device to actuate the latter, and trigger mechanism operable from the exterior of the machine to load said spring and thereby render it effective to actuate the feeding device and when fully loaded to release it. 10

15. A manifold writing device for issuing tickets comprising a ticket strip supply magazine adapted to accommodate a supply of at least two superimposed ticket strips, a feeding mechanism for the strip normally inaccessible from the exterior of the device and provided with means arranged to engage with perforations in the strips so as to feed each of said strips forwardly 15 at least one ticket length upon each actuation of the device, a spring loaded trigger operated driving mechanism for said feeding mechanism operable from the exterior of the device, and means for feeding the leading end of at least 20 one of the superimposed strips to the exterior of the device and at least one to the interior, upon each actuation of the feeding mechanism. 25

16. A strip ticket issuing machine comprising a ticket strip supply magazine adapted to accommodate a supply of at least one ticket strip, 30 a feeding device for the strip normally inaccessible from the exterior of the machine and provided with means arranged to engage with perforations in the strip so as to feed said strip forwardly at least one ticket length upon each actuation of the machine, a yieldingly controlled mechanism arranged to actuate said feeding device and a trigger device operable from the exterior of the machine to load said mechanism 40 and then automatically release it for actuation of the feeding device.

17. A strip ticket issuing machine comprising a ticket strip supply magazine adapted to accommodate a supply of at least one ticket strip, 45 a feeding device for the strip normally inaccessible from the exterior of the machine and provided with means arranged to engage with perforations in the strip so as to feed said strip forwardly at least one ticket length upon each 50 actuation of the machine, a spring-loaded mechanism operable to actuate said feeding device, a trigger device manually operable from the exterior of the machine for moving the said mechanism in one direction against the tension of 55 its loading spring, and means for automatically releasing the mechanism after the trigger device has been operated a predetermined distance so that the said mechanism moves under the action of the spring in the reverse direction and 60 thereby actuates the said feeding device. 65

18. A strip ticket issuing machine comprising a ticket strip supply magazine adapted to accommodate a supply of at least one ticket strip, a feeding device for the strip normally inaccessible from the exterior of the machine and provided with means arranged to engage with perforations in the strip so as to feed said strip forwardly at least one ticket length upon each actuation of the machine, a pivoted lever, manual means accessible from the exterior of the machine for displacing said lever in one direction, a second lever, means operatively connecting the second lever to the feeding device so as to be capable of operating the same upon move- 70 75

- ment in one direction, a loading spring for said second lever operative when released to actuate the lever in said direction in which it operates the feeding device, means normally to couple 5 the two levers together for movement in unison during the initial part of the manual displacement of the first lever and means for automati-

cally releasing the second lever from the first towards the end of the stroke of manual displacement thereof whereby to cause the second lever to actuate the feeding device.
